UNITED STATES PATENT OFFICE.

JEREMIAH A. SCRIVEN, OF NEW YORK, N. Y.:

NETHER GARMENT.

SPECIFICATION forming part of Letters Patent No. 690,196, dated December 31, 1901.

Application filed April 4, 1901. Serial No. 54,240. (No model.)

To all whom it may concern:

Be it known that I, JEREMIAH A. SCRIVEN, a resident of the borough of Manhattan, city, county, and State of New York, have invented 5 certain new and useful Improvements in Nether Garments, of which the following is a specification.

My invention relates to nether garments, more particularly to drawers, although my 10 invention is not confined to nether garments or drawers.

In the accompanying drawings, forming a part hereof, in which like reference-letters indicate like parts, Figure 1 represents a pair of 15 drawers embodying my invention and upon the person of the wearer. Fig. 2 is a rear view of the drawers. Fig. 3 is a section on line 3 3 of Fig. 2. Fig. 4 is an underneath view of the crotch of the garment; and Fig. 5 20 is a section on line 5 5 of Fig. 4, showing the mode of making the crossing of the insertions.

In the drawings, *a* and *b* indicate the material from which the tubular leg portions and the tubular body portions are made. As 25 shown in Figs. 1 and 2, each of these portions *a* *b* is very large and with the exception of the insertions hereinafter mentioned and the small gussets or gores *c* constitute the leg portions of the garment and the greater part of 30 the body.

d and *e* are insertions of a material less elastic than the material constituting the portions *a* and *b*. These insertions cross at the crotch of the garment and are herein shown 35 as at the back of the garment. The lower end of the insertion *d* is sewed to the piece *a* by lines of stitching *f* *g*, except at the bottom, where the small gore *c* is set in. The insertion *e* is similarly secured to the material of 40 the other tubular member, which is similarly constructed, by lines of stitching *h* *i*. A suitable triangular or other shaped back piece *j* is let into the back of the garment below the waistband *k*. The upper end of the insertion 45 *e* is secured by a line of stitching *l* to the piece *a* and by a line of stitching *m* to the triangular piece *j*. The upper end of the insertion *d* is secured by a line of stitching *o* to the member *b* and by line of stitching *p* to 50 the piece *j*. The garment may likewise be provided with anklets *q* *r*. The insertions *d* and *e* cross at or near the crotch of the gar-

ment, whether they be inserted in the front of the garment or in the back of the garment, and lines of stitching *s*, which form part of 55 the lines of stitching uniting the insertion to the garment, serve to unite the cross-insertions firmly to each other at the crossing.

It will be understood that the garment may be made of any suitable material and that the 60 portions *a* and *b* are of greater elasticity than the cross-insertions *d* and *e*.

The material which I use for the elastic portion of my garment is what is known in the trade as "knitted" fabric. The material 65 which I use for the inelastic insertion is cotton woven fabric, twill, jean, linen, or any other suitable comparatively inelastic material.

The inelastic insertions *d* and *e*, extending, respectively, from left to right and from right 70 to left of the garment, constitute practically rigid diagonal braces that tend to hold the garment in shape and position and at the same time serve to produce economy in its manufacture.

The particular advantages of a nether garment constructed in accordance with my invention are that it will not shrink in the direction of its length and will keep its form, that the relatively inelastic insertion will act 80 as a guide for the foot in slipping into and through the tubular portions of the garment, and that the life of the garment will be longer, because the tubular portions are less liable to be torn by the foot than in a garment in which said portions shrink or twist. 85 Such a garment can also more readily withstand the strain to which it is periodically exposed in the washtub. All these advantages are gained without any discomfort to the 90 wearer or by adding appreciably to the thickness of any portion of the garment.

Having described my invention, what I claim, and desire to secure by Letters Patent, is—

1. An undergarment consisting of a body and leg portions comprising a knitted elastic fabric provided with non-elastic-fabric inserts or separating-strips, extending from substantially the bottom of said garment to substantially the crotch thereof, whereby the garment may be drawn onto the person of the wearer and the leg portions be guided by the non-elastic inserts.

2. An undergarment consisting of a body and leg portions comprising a knitted elastic fabric provided with non-elastic-fabric inserts or separating-strips, extending from substantially the top to substantially the bottom thereof whereby the elastic garment may be drawn onto the person of the wearer and the leg portions be guided by the non-elastic inserts and the entire garment be stiffened as set forth.
3. An undergarment consisting of a body and leg portions comprising a knitted elastic fabric provided with non-elastic-fabric in-

serts or separating-strips, crossed at the crotch of the garment, and extending from substantially the top to substantially the bottom thereof whereby the elastic garment may be drawn onto the person of the wearer and the leg portions be guided by the non-elastic inserts, and the entire garment be stiffened, as set forth.

JEREMIAH A. SCRIVEN.
